UNITED STATES PATENT OFFICE

CARL OTTO, OF ESSEN-RUHR, GERMANY

CLOSURE FOR COKE OVEN CHAMBERS

Application filed November 21, 1927, Serial No. 234,851, and in Germany November 26, 1926.

The invention relates to self-sealing coke oven doors, in which a sealing plate which is elastic such as a diaphragm, is arranged on the door frame, which plate is adapted to be pressed against a sealing frame arranged on the outer door aperture. The object of my invention is to improve this known manner of sealing coke oven chambers in order to provide a gastight closure; the door frame being fixed, in its position on the buckstays of the oven by clamping, and adjusting means being provided, which allow the adjustment of the sealing plate independently of the main clamping means. This arrangement enables the sealing pressure to be distributed on the entire circumference of the sealing plate in a completely uniform manner, and local leakages or overstresses to be compensated for, without it being necessary to re-adjust in any way the main clamping means. This clamping means may be of an extremely simple construction, so that it may be applied and withdrawn in a very short time. The invention thus offers a coke oven door which is very easy to operate and secures a perfect sealing effect. This is a particular advantage of the door according to my invention as compared with hitherto known self-tightening doors, in which the adjusting of the packing means is only obtained at the cost of simple operation.

In order to allow my invention to be more easily understood, a preferred embodiment of same is illustrated by way of example in the drawings which accompany and form part of this specification. In the drawings:

Fig. 1 is a horizontal section on the line 1—1 of Figure 2.

Fig. 2 is an elevation showing the parts in place in the chamber aperture.

Fig. 3 is a detail view showing the screw bolts for adjustably pressing the elastic sealing plate against the sealing frame.

Figure 4 is a detail cross section of the preliminary pressure means.

Referring to these figures, the coke oven door, which is designed in the usual manner as a stopper door, has an outer frame a^1 that carries the stopper a of refractory material, and abutting sealing surfaces a^2 adapted to

abut on corresponding surfaces b^1 of the stationary door frame b . The frame a^1 has mounted on it a diaphragm-like elastic sealing plate c which, when the door is closed, abuts on a sealing frame d arranged on the edge of the outer chamber aperture, the frame d being preferably provided with an acute sealing edge d^1 . Cross bars e are fixed on ribs a^3 of the door frame a^1 , which bars carry a frame f disposed opposite the sealing edges d^1 . Presser screw bolts g are arranged on the frame f around its perimeter at suitable distances apart, and constitute an adjusting means which abut with their free ends on a presser frame h fastened on the sealing plate c , (see Figure 3) or, if frame h is dispensed with abut immediately on this plate itself. The clamping of the door frame a^1 may be effected in a known manner by the cross bars e , which are rigidly fixed on frame a^1 , being held in their position relatively to the oven chamber by wedges k and other cross bars n resting in suitable holes provided in the buckstays m . To relieve the pressure bolts g , from load rigid projections such as presser pieces o may be arranged on the bars e of frame f which pieces permanently abut on the presser frame h , whereby a certain preliminary pressure may be obtained (see Figure 4).

When the door is to be inserted, it is slid into the aperture of the chamber, until the surfaces a^2 of the door abut on the corresponding surfaces b^1 of the stationary door frame b . Thereupon the cross bars n are inserted in the respective holes of the buckstays m and the wedges k are driven between the bars n and the bars e rigidly fixed on the door frame a^1 , whereby the door is clamped and closed. The diaphragm-like elastic tightening plate c is thereby urged against the sealing edge d^1 of the frame d by means of the presser pieces o and presser bolts g . The desired sealing effect is thus obtained.

Now, when local leakages or overstresses of the packing occur due to heat stresses or warping, merely the presser bolts g need to be adjusted correspondingly, without the secure clamping of the door being influenced thereby in any way. By this arrangement

and by limiting the insertion of the door in the chamber aperture by the abutting surfaces a^2 and b^1 , an extraordinary low wear of the packing means, plate c and frame d is obtained. For, according to my invention, the plate c and frame d merely serve to seal the door, whilst the clamping pressure is taken up by the strong bars e and the door frame a^1 . A notable relief of the packing means from load is also obtained by this arrangement.

Having thus described the invention it will be understood that changes may be made in carrying the invention into effect, without departing from the principle thereof.

What I claim and desire to secure by Letters Patent, is:—

1. In a coke oven, a stationary door frame, a door body, abutting sealing surfaces on said door frame and said door body, a stationary sealing frame mounted adjacent to the door frame and provided with an abutting sealing surface, an elastic sealing plate arranged on said door body and adapted to engage with said last-named sealing surface, clamping means adapted to close the door and to press said door body and said sealing plate against the respective abutting and sealing surfaces, and means for transmitting the pressure exerted by said clamping means to said sealing plate and to said door body.

2. In a coke oven, a stationary door frame, a door body, abutting sealing surfaces on said door frame and said door body, a stationary sealing frame mounted adjacent to the door frame and provided with an abutting sealing surface, an elastic sealing plate arranged on said door body and adapted to engage with the sealing surface of said stationary sealing frame, clamping means adapted to press said door body and said sealing plate against the respective abutting and sealing surfaces, means for transmitting the pressure exerted by said clamping means to said sealing plate and to said door body, and means for varying said pressure.

3. In a coke oven, a stationary door frame, a door body, abutting sealing surfaces on said door frame and said door body, a stationary sealing frame mounted adjacent to the door frame and provided with an abutting sealing surface, an elastic sealing plate arranged on said door body and adapted to engage with said last-named sealing surface, clamping means adapted to press said door body and said sealing plate against the respective abutting and sealing surfaces, a frame rigidly fixed on said door body and adapted to be acted upon by said clamping means and presser screw bolts mounted on said last-named frame and adapted to act upon said sealing plate.

4. In a coke oven, a stationary door frame, a door body, abutting sealing surfaces on

said door frame and said door body, a stationary sealing frame mounted adjacent to the door frame and provided with an abutting sealing surface, an elastic sealing plate arranged on said door body and adapted to engage with said last-named sealing surface, clamping means adapted to press said door body and said sealing plate against the respective abutting and sealing surfaces, a frame rigidly fixed on said door body and adapted to be acted upon by said clamping means, and presser screw bolts mounted on and distributed over the perimeter of said last-named frame and adapted to act upon said sealing plate.

5. In a coke oven, a stationary door frame, a door body, abutting sealing surfaces on said door frame and said door body, a stationary sealing frame mounted adjacent to the door frame and provided with an abutting sealing surface, an elastic sealing plate arranged on said door body and adapted to engage with said last-named sealing surface, clamping means adapted to press said door body and said sealing plate against the respective abutting and sealing surfaces, a frame rigidly fixed on said door body and adapted to be acted upon by said clamping means, presser screw bolts mounted on and distributed over the perimeter of said last-named frame and adapted to act upon said sealing plate, and means for transmitting to said sealing plate a portion of the pressure exerted upon said last-named frame, independently of said screw bolts.

6. In a coke oven, a stationary door frame, a door body, abutting sealing surfaces on said door body and said door frame, a stationary sealing frame mounted adjacent to the door frame and an abutting sealing surface on said frame, an elastic sealing plate arranged on said door body and adapted to engage with said last-named sealing surface, clamping means adapted to press said door body and said sealing plate against the respective abutting and sealing surfaces, a frame rigidly fixed on said door body and adapted to be acted upon by said clamping means, presser screw bolts mounted on and distributed over the perimeter of said last-named frame and adapted to act upon said sealing plate, rigid projections on said last-named frame and adapted to abut on said sealing plate, when the door is inserted, prior to said presser screw bolts.

7. In a coke oven, a stationary door frame, a door, metallic sealing members between the door and frame, said sealing members including a metal plate and a metal sealing frame having an edge and abutting sealing surface, one member being secured to the door and the other to the door frame, and clamping means for bringing said members into sealing engagement.

8. In a coke oven, a stationary door frame,

- a door, metallic sealing members between the door and frame, said sealing members including a metal plate and a metal sealing frame having an edged and abutting sealing surface, one member being secured to the door and the other to the door frame, and clamping means for bringing said members into sealing engagement and separate means for tightening the sealing members.
- 5 9. In a coke oven, a door frame provided with shoulders extending toward each other, a door having an outer shell adjoining said shoulders, said door frame, shoulders and shell being arranged to define three sides of a
- 10 chamber at each side of the door, metallic sealing members between the door and door frame adapted to close the fourth side of said chambers, said sealing members including a metal plate and a metal sealing frame having an edged and abutting sealing surface, one member being secured to the door and the other to the door frame, and clamping means for bringing said members into sealing engagement and separate means for tightening
- 15 20 25 the sealing members.
